RAILWAY TRUCK

Glenn F. Couch, Rochester, N. Y., assignor to The Symington-Gould Corporation, Rochester, N. Y., a corporation of Maryland

Application April 21, 1941, Serial No. 389,669

15 Claims. (Cl. 105—190)

This invention relates to railway trucks and more particularly to a type thereof having a bolster adapted to move laterally or transversely of the truck relative to a transom and side frames.

An object of the invention is the provision, in a railway truck, of a transom movable vertically but prevented from angling horizontally relative to supporting side frames.

Another object of the invention is the provision, in a railway truck, of a transom resiliently supported by side frames and in turn resiliently supporting a bolster with both sets of springs having their oscillations or vibrations checked, snubbed, damped or controlled.

A further object of the invention is the provision, in a railway truck, of a side frame having a bolster opening and carrying a nest of coil springs, a transom supported by the nest of coil springs and arranged with the side frame so as to prevent a horizontal angling motion of the transom relative to the side frame and a bolster of shorter length than the transom supported by the latter through a second nest of coil springs.

An added object of the invention is the provision, in a railway truck, of a transom supported by a side frame through a group of snubbed or controlled coil springs and a bolster adapted to move transversely or laterally of the truck and supported by the transom through the medium of a nest of damped or snubbed coil springs.

A still further object of the invention is the provision, in a railway truck, of a friction means for checking the recoil of the transom supporting springs and a friction means for controlling both the expansive and compressive action of a group of lateral motion bolster supporting springs.

The above objects as well as numerous others will be apparent from the succeeding description when considered together with the accompanying drawings which disclose in several views an arrangement of parts forming a railway truck embodying the present invention.

Referring in a general manner to the drawings wherein:

Figure 1 is a front view, shown partly in elevation and partly in section, of a portion of a railway truck embodying the present invention.

Figure 2 is a top view of the railway truck shown partly in plan and partly in horizontal cross section, taken along the lines 2—2 of Figure 1, looking in the direction of the arrows, and of reduced size.

Figure 3 is a transverse view of the railway truck shown partly in section and partly in ele-

vation and taken along the lines 3—3 of Figure 2, looking in the direction of the arrows.

Figure 4 is an enlarged sectional view taken along the lines 4—4 of Figure 3, looking in the direction of the arrows.

Referring now in detail to the drawings wherein like reference characters indicate like parts, the numeral 1 is employed to designate a railway truck formed, in part, by side frames 2 extending longitudinally of the truck adjacent and defining the lateral limits thereof. Only a portion or, for the present purpose, the most pertinent part of one side frame is illustrated in the drawings since the undisclosed part thereof may follow the teachings of Patent No. 2,132,382, granted to Donald S. Barrows under date of October 11, 1938, and entitled Railway trucks. Only the disclosed portion of one illustrated side frame will be hereinafter described, it being clearly understood that the pair of side frames of the present structure is of identical construction in every detail and respect.

The side frame comprises a top chord or compression member 3 spaced vertically from a bottom chord or tension member 4, both of which are joined intermediate their ends by longitudinally spaced vertically extending guide columns 5 which define a window opening 6 therebetween. Each guide column is desirably channel- or U-shaped in horizontal cross section so as to open, at least throughout the major upper portion thereof, inwardly of the window opening for the purpose to be hereinafter explained. Accordingly, each guide column is formed by a transversely disposed substantially vertical web 7 which defines the longitudinal limits of the window opening and has, extending from the transverse edges thereof, laterally spaced reentrant inner and outer flanges 8 and 8^a, respectively, which have their upper extremities merging with aligned portions of the compression member and their lower or free extremities terminating short of the tension member. The tension member is desirably of a width transversely of the truck, so as to accommodate a single row of coil or helical springs 9 forming a nest or group of resilient means positioned on or disposed along the longitudinal axis of the side frame and prevented from being dislodged or accidentally shifted from the side frame by transversely spaced ribs 10 which extend between and merge with the guide columns to define a spring seat 11 on the tension member.

Forming a connection between the side frames is a transom, load carrying member or transom

bolster 12 formed by longitudinally spaced, transversely extending, intermediate and desirably hollow beams 13 comprising horizontally spaced, vertically disposed inner and outer walls 14 and 15, respectively, integrally connected adjacent their vertical limits by horizontally directed upper or top and lower or bottom walls 16 and 17, respectively. The two beams merge into transom heads or units adjacent the ends of the transom to form transom extremities 18 of box-like formation. Each transom extremity comprises a horizontal, upper or top wall 16^a spaced vertically from or a predetermined distance above a correspondingly disposed lower or bottom wall 17^a, the latter of which is of sufficient extent to blanket or overlie and bear upon the subjacent nest or group of resilient means 9. The beam outer walls 15 are extended laterally, as at 15^a, to form outer walls for each transom extremity and lie spaced a predetermined distance inwardly of, but in the close proximity to, an associated column guide. The inner wall of each beam, as it approaches the inner vertical limits of a related side frame, is directed longitudinally of the truck toward a transverse vertical plane bisecting the window opening where it merges with a correspondingly directed inner wall to form an intermediate, vertical wall 18^a which joins the transom end upper and lower walls and forming a stiffening or reinforcing member for the associated box-like transom extremity.

The use of coil or helical springs of the same size to support the transom extremity is desirable in the present construction since they will effect an easier or smoother riding truck and are, as compared with spring means of other characters or types, considered more sensitive or responsive to external impulses imparted to the truck structure caused by the wheels (not shown) of the truck while in transit, passing over contiguous rail extremities, switches and other irregularities in the rails. In employing a nest of springs of the same characteristics care must be exercised to avoid a synchronization of the oscillations or vibrations of the springs as a group with the external impulses because of the damaging effects thereof. If, for instance, the vibrations of the transom supporting springs were permitted to synchronize with the external impulses transmitted to the truck, the springs would be driven solid upon a compressive movement thereof while upon an expansive movement or recoil they would be extended beyond their normal free height. This harmonic spring action would not only result in damage to the springs themselves but would also subject the truck to severe impulses which would ultimately terminate in failure of the component parts and derailment of the truck. In order to avoid such a contingency and still retain the aforementioned desirable qualities flowing from the use of a group of coil springs, means has been included in the structure to snub, check, retard or dampen the harmonic action of the springs. Since any external impulses imparted to the truck will cause a deflection of the transom supporting springs it is intended to permit a free unrestricted compressive movement of the springs to obtain the full cushioning effect thereof. It is further intended, by use of the hereinafter described arrangement of parts, to snub or check any tendency of the springs to synchronize with the external impulses only during an expansive movement or recoil of the springs.

Toward the accomplishment of the above, 75

there is provided, outwardly and integrally formed with each transom extremity outer wall 15^a, an arm, shoe or triangular-shaped block 19 extending into a related column guide and having a plane vertical surface 20 facing inwardly of the truck and provided with a wear plate 20^a, the latter of which is adapted to bear against and frictionally engage a correspondingly disposed wear plate 21 carried by the column inner flange 8. The arms of each transom end are arranged to react inwardly of the truck against the related column flanges, and for this reason the transom will not be permitted to angle in a horizontal manner relative to the side frames. Accordingly, the two side frames of the truck will be maintained at all times in true transverse alignment to present a rigid or square structure insofar as the side frames and transom are concerned. Intimately associated with each transom shoe and also housed by a related column guide is a wedge or adjustable block 22 having a plane vertical surface 23 substantially parallel with the shoe surface 20 and bearing against and in frictional engagement with a correspondingly disposed wear plate 24 carried by the column outer flange 8^a. Each wedge is provided with a tapered or inclined surface 25 disposed in an inward and upward direction and arranged to bear upon a juxtaposed surface 26 carried by the transom shoes. By thus disposing the surfaces 25 and 26 it will be noted that upon a downward motion of the transom and a deflection of the subjacent springs the shoes will tend to move away from the wedges to result in a very negligible degree of frictional forces being created on the contacting surfaces of the shoes, wedges and column flanges. However, upon a recoil or expansive movement of the transom supporting springs the surfaces 25 and 26 will tend to increase the horizontal distance between the wedge surface 23 and the shoe wear plate 20^a to thereby materially increase the lateral pressure against the column flanges and snub the recoil action of the springs.

So as to maintain the shoes and wedges in a predetermined relation, each shoe is provided with a ledge or shelf 27 which underlies the associated wedge and extends outwardly of the truck toward the adjacent column outer flange. The ledges desirably merge with the extremity outer wall 15^a in the horizontal plane of the bottom wall 17^a. Each wedge is of hollow, skeletonized form to not only reduce the weight thereof but to also accommodate a compression or coil spring 28 reacting between or vertically against the wedge and a superimposed spring cap or plate 29. Extending through each spring cap, wedge and an accommodating aperture in the subjacent ledge is a bolt or tie means 30 having a head portion 30^a underlying the ledge and a rotatable means, adjusting element or nut 30^b superimposed upon the spring cap. By a manipulation of the nut 30^b the effective length of the bolt may be changed or adjusted as desired to selectively control or determine the compressive value of the spring 28 and the degree of frictional forces created on the column wear plates and engaging surfaces.

In order to incorporate a certain degree of flexibility in the present truck to the extent that an allowance is made for a lateral motion of a supported car body (not shown) with respect to the side frames and transom in response to lateral thrusts to which the truck will be subjected in service, there is provided an inner bolster, lat-

eral motion bolster or load carrying member 31 of relatively shorter extent or length than the transome bolster. The lateral motion bolster carries, intermediate its ends, the usual truck center plate 32 arranged to mate with a correspondingly formed body center plate (not shown) which forms the medium through which the truck may pivot beneath the car body as the railway vehicle is executing a curve. The lateral motion bolster, adapted to move transversely of the truck between the transom beams, desirably comprises a top wall 33 spaced vertically from and above a bottom wall 34, both of which, adjacent their corresponding free edges, are integrally joined by vertically disposed and spaced side walls 35 to form a hollow, rigid girder-like structure. The top wall, adjacent the longitudinal extremity of the lateral motion bolster, terminates in downwardly directed end walls 36 which are spaced a predetermined distance away from the transom intermediate wall 18 by an amount which is determinative of the permissible transverse movement of the inner bolster.

Supporting movable means is associated with the transom and inner bolster so as to facilitate a transverse movement of the latter mentioned bolster, and as characteristic of such a means the beam upper walls are provided with a plurality of suitably spaced upstanding lugs 37 to define or form upwardly opening saddle or cylindrical bearings 38 therebetween. The saddle defining lugs are positioned adjacent each longitudinal extremity of each transom beam in close proximity to the associated extremity of the inner bolster. The beam upper and lower walls 16 and 17 are provided with apertures or openings 39, the upper of which are disposed in planes between the upstanding lugs. Swing hangers or links 40 extend through the beam openings to have their upper ends formed or fitted with cylindrical, cross, pivot or shear pins 41 which nest in the saddles so that the hangers may pivot or move about a given axis transversely of the truck. As will be noted, two hangers in alignment are arranged in the transom at each side of a longitudinal axis of the truck so that a pair of hangers is positioned on each side of the truck between the side frame and center bearing or plate. The hangers are of such length that they extend a predetermined distance below the horizontal plane of the beam lower walls, and accordingly associated hangers have their lowermost extremities connected by means of a cylindrical tie bar 42, which may be secured to the links by any desired means, such as the illustrated lock pins 43. Each set of hangers and tie bar forms a stirrup suspended from the transom beams inwardly of the truck from the adjacent side frame. Pivotally mounted on each stirrup tie bar is a spring plate or casing 44 formed, in part, by a base plate 45 having depending, longitudinally extending, transversely spaced, flanges 46 which define a downwardly facing or opening semi-cylindrical cradle 46a for engagement by or accommodation of the related tie bar. A plurality of gussets or ribs 46b of triangular formation extend between each spring plate flange and the base plate outwardly of the cradle to rigidify the flanges against stresses to which they will be subjected in service.

The inner bolster is provided with a downwardly opening pocket 47 adjacent each end thereof which is in substantially vertical alignment with the underlying spring plate base. Each inner bolster pocket is defined by portions

5 of the side walls 35, the related end wall 36 and an intermediate barrier, partition or transverse wall 48 and closed at its top extremity by the overlying top wall 31. Positioned or housed within each bolster pocket is a nest or group of resilient means characterized by a plurality of, preferably four, helical or coil springs 49 arranged to act in series with the transom supporting springs to facilitate a long spring travel and react vertically against the inner bolster top wall and the oppositely disposed spring plate. This nest of springs, like the group 9, is formed preferably of the coil type so as to be quickly responsive to external impulses transmitted to the truck in service as well as fully and adequately cushion the load of the superimposed car body (not shown) and thereby eliminate damage to the lading within the car body. In order to avoid a synchronization of the vibrations of the inner bolster springs with any external impulses which may be imparted to the truck at regular or periodic intervals a snubbing means has been provided to check or retard a free compressive and expansive movement of this group of springs. 10 As exemplary of such a means each spring plate is formed with an upwardly directed inner flange, wall or leg 50 desirably parallel and in telescoping relation with the inner bolster barrier and extending into a related bolster pocket. A wear or friction plate 51 carried by the inner leg bears against and is in frictional engagement with a correspondingly disposed friction or wear plate 52 which is secured to the inner bolster partition by any desired means, such as welding (not shown). It will be noted by referring particularly to Figure 3 of the drawings that the links are disposed off center or inclined with respect to the vertical to be directed downwardly and outwardly of the truck from the cross pins 41. 15 By thus disposing the links the spring plates actuated by the superimposed load will at all times be urged toward the center of the truck to maintain the wear plate 51 in intimate and frictional contact with the barrier wear plate 52. Accordingly, any deflection of the springs 49 will create frictional forces on the juxtaposed wear plate surfaces to not only add to the capacity of the group of springs but to disturb any harmonic actions thereof. Since frictional forces 20 will be created on the engaging surfaces of the wear plates 51 and 52 during any vertical relative movement between the inner bolster and spring casing, any movement of the inner bolster transversely of the truck from its normal or illustrated position will result in the spring casings being urged in the same direction to alter their vertical positions and thereby result in controlling the lateral movement of the inner bolster.

25 The inner leg of each spring plate is reinforced by spaced triangularly shaped side legs 53, while the latter have their ends, removed from the end leg, connected by an outer flange or wall 54 to complete a circumambient means upstanding from the spring plate base which prevents an accidental or unwarranted displacement of the springs 49. A rub, guide or wear plate 55 is secured to each inner bolster side wall outwardly thereof and is spaced a slight distance from a guide or wear plate 56 which is fastened to the beam inner wall. The wear plates 55 and 56 are adapted to guide the inner or lateral motion bolster throughout its permissive range of transverse travel as well as limit the movement of the inner bolster in a direction longitudinally of the truck.

From a consideration of the accompanying drawings and the preceding description it will be noted that various changes and alterations may be made to the illustrated structure without departing from within the spirit and scope of the appended claims.

I claim:

1. In a railway truck of the type having a side frame provided with spaced channel-shaped guide columns facing one another and connected adjacent their lower extremities by a tension member, the combination of a transom having an end portion positioned between said guide columns, a group of coil springs supported by said tension member and in turn supporting said transom end, friction means positioned in and constantly contacting said guide columns and adapted to prevent a horizontal angular movement of said transom relative to said side frame, hanger means including friction means carried by said transom inwardly of said side frame, a group of coil springs carried by said hanger means, and a bolster having an end supported by said last named group of coil springs and engaging said friction means.

2. In a railway truck of the type having a side frame provided with spaced channel-shaped guide columns facing one another and connected adjacent their lower extremities by a tension member, the combination of a transom having an end portion positioned between said guide columns, a group of coil springs supported by said tension member and in turn supporting said transom end, friction means positioned in said guide columns and adapted to prevent a horizontal angular movement of said transom relative to said side frame, hanger means carried by said transom inwardly of said side frame, and a group of coil springs carried by said hanger means and extending into a bolster, and said bolster having an end supported by said last named group of coil springs, said bolster and hanger means having confronting faces in constant bearing relation with one another so that frictional forces are created thereon to snub the action of the bolster supporting springs.

3. In a railway truck of the type having a side frame provided with spaced channel-shaped guide columns facing one another and connected adjacent their lower extremities by a tension member, the combination of a transom having an end portion positioned between said guide columns, a group of coil springs interposed between said transom end and tension member, friction means positioned in said guide columns for snubbing the expansive movement of said coil springs and permitting a comparatively unrestricted compressive movement thereof, hanger means associated with said transom, a group of coil springs carried by said hanger means, and a bolster having an end supported by said last named group of coil springs.

4. In a railway truck of the type having a side frame provided with spaced channel-shaped guide columns facing one another and connected adjacent their lower extremities by a tension member, the combination of a transom having an end portion positioned between said guide columns, a group of coil springs interposed between said transom end and tension member, friction means positioned in said guide columns for snubbing the expansive movement of said coil springs and permitting a comparatively unrestricted compressive movement thereof, hanger means associated with said transom, a group of coil springs carried by said hanger means, and a bolster having an end

supported by said last named group of coil springs; said hanger means and bolster having vertically disposed faces in constant contact so that frictional forces are created thereon to snub the action of the bolster supporting springs.

5. In a railway truck of the type having a side frame provided with spaced channel-shaped guide columns facing one another, the combination of a transom having an end portion positioned between said columns, coil spring means carried by said side frame and supporting said transom end, arms outstanding from said transom end extending into said guide columns for preventing a horizontal angular movement of said transom relative to said side frame, means associated with said arms for maintaining the latter in intimate contact with said guide columns, supporting means associated with said transom, coil springs carried by said supporting means, and a bolster supported by said coil springs.

6. In a railway truck of the type having a side frame provided with spaced channel-shaped guide columns facing one another, the combination of a transom having an end portion positioned between said columns, coil spring means carried by said side frame and supporting said transom end, arms outstanding from said transom end in constant intimate contact with said guide columns for preventing a horizontal angular movement of said transom relative to said side frame, means associated with said arms for maintaining the latter in intimate contact with said guide columns, supporting means associated with said transom, coil springs carried by said supporting means, and a bolster supported by said coil springs, said supporting means and bolster having plane surfaces in constant contact with one another irrespective of the position of the bolster so that frictional forces are created constantly thereon to snub the action of said coil springs.

7. In a railway truck of the type having a side frame provided with spaced channel-shaped guide columns facing one another, the combination of a transom having an end portion positioned between said columns, coil spring means positioned on a longitudinal axis of said side frame and supporting said transom end, means integral with said transom end outstanding therefrom to extend into said columns, means associated with said integral means and columns for preventing a horizontal angular movement of said transom and snubbing the recoil of said coil spring means, supporting means associated with said transom, coil springs carried by said supporting means, and a lateral motion bolster bearing upon said coil springs.

8. In a railway truck of the type having a side frame provided with spaced channel-shaped guide columns facing one another, the combination of a transom having an end portion positioned between said columns, coil spring means positioned on a longitudinal axis of said side frame and supporting said transom end, means integral with said transom end outstanding therefrom to extend into said columns, means associated with said integral means and columns for preventing a horizontal angular movement of said transom and snubbing the recoil of said coil spring means, supporting means associated with said transom, coil springs carried by said supporting means, and a lateral motion bolster bearing upon said coil springs, said supporting means having a portion thereof adapted to move transversely of said truck and frictionally engage said

lateral motion bolster upon a vertical action of said associated coil springs.

9. In a railway truck, the combination of a transom bolster, supporting means pivotally associated with said transom bolster, spring means associated with said supporting means, and a lateral motion bolster positioned within the confines of said transom bolster and bearing upon said spring means, said supporting means having a wall inwardly of said truck and carrying a surface in constant frictional engagement with said lateral motion bolster to snub the action of said spring means.

10. In a railway truck, the combination of a transom bolster, supporting means pivotally associated with said transom bolster, a spring plate carried by said supporting means, a group of coil springs bearing upon said spring plate, and a lateral motion bolster housing and bearing upon said group of coil springs, said lateral motion bolster being within the horizontal limits of said transom bolster; said spring plate having a surface at one end inwardly of said truck in constant frictional engagement with said lateral motion bolster to snub the action of said group of coil springs.

11. In a railway truck, the combination of a transom bolster, supporting means movably associated with said transom bolster, a spring casing pivotally carried by said supporting means, a group of springs bearing upon said spring casing, and a lateral motion bolster housing and bearing upon said group of springs, said spring casing being supported in such a manner as to constantly tend to be urged inwardly of said truck and contact said lateral motion bolster so as to create frictional forces upon a vertical action of said group of springs.

12. In a railway truck, the combination of a resiliently mounted snubbed transom bolster, means suspended from said transom bolster, a spring plate pivotally supported by said suspended means and having an inner upstanding wall, a nest of coil springs bearing upon said spring plate, and a lateral motion bolster bearing upon

said nest of coil springs and reacting constantly outwardly of said truck against said upstanding wall.

13. In a railway truck, the combination of a resiliently mounted snubbed transom bolster, supporting means movably associated with said transom bolster, a spring casing pivotally mounted on said supporting means, a group of coil springs carried by said spring plate, and a lateral motion bolster bearing upon said group of coil springs; said lateral motion bolster and spring plate being telescopingly related and in bearing relation with one another so as to constantly create frictional forces upon a vertical action of said group of coil springs.

14. In a railway truck, the combination of a transom bolster, a lateral motion bolster having a downwardly opening pocket adjacent an end thereof, supporting means pivotally mounted on and carried by said transom bolster, an upwardly opening spring casing pivotally mounted on said supporting means and extending into said lateral motion bolster pocket, and a group of coil springs positioned in said pocket and interposed between said spring casing and lateral motion bolster; said spring casing being urged inwardly of said truck and adapted to constantly frictionally engage said lateral motion bolster upon a vertical action of said group of coil springs.

15. In a railway truck, the combination of a transom bolster, a lateral motion bolster having a downwardly opening pocket adjacent an end thereof, supporting means mounted on said transom bolster, a spring casing pivotally mounted on said supporting means and extending into said lateral motion bolster pocket, and resilient means positioned in said pocket and interposed between said spring casing and lateral motion bolster, said spring casing being urged constantly inwardly of said truck irrespective of the transverse location of said lateral motion bolster and thereby adapted to frictionally engage said lateral motion bolster.

GLENN F. COUCH.
